(57) **CLAIM**

The ornamental design for a rake head, as shown and described.

DESCRIPTION

FIG. 1 is a top, front, left side perspective view of a rake head;

FIG. 2 is a right side elevational view thereof with the handle removed;

FIG. 3 is a top plan view thereof;

FIG. 4 is a bottom plan view thereof;

FIG. 5 is a front elevational view thereof; and,

FIG. 6 is a rear elevational view thereof.

The broken line showing of the handle is included for the purpose of illustrating environment and forms no part of the claimed design.
